DESIGN FOR A CIGARETTE CASE OR SIMILAR ARTICLE

George W. Headley, 3rd, New York, N. Y., assignor to Paul E. Flato, New York, N. Y.

Application January 6, 1938, Serial No. 74,112

Term of patent 3½ years

To all whom it may concern:

Be it known that George W. Headley, 3rd, a citizen of the United States and resident of New York city, in the county of New York and State of New York, has invented a new, original, and ornamental Design for a Cigarette Case or Similar Article, of which the following is a specification, reference being had to the accompanying drawing forming part thereof, in which,

Fig. 1 is a top plan view of a cigarette case embodying my design.

Fig. 2 is a side view thereof.

Fig. 3 is a rear view thereof.

Fig. 4 is a front view thereof.

Fig. 5 is another side view thereof; and

Fig. 6 is a bottom plan view thereof.

I claim:

The ornamental design for a cigarette case or similar article, substantially as shown.

GEORGE W. HEADLEY, 3RD.
